INTEGRAL HOSE AND NOZZLE

Clarence W. Borden, John Kocsis and Francis William Kubala, Trenton, N.J., assignors to Goodall Rubber Company, Trenton, N.J., a corporation

Filed July 2, 1968, Ser. No. 12,596

Term of patent 14 years

Int. Cl. D23—01

U.S. Cl. D23—34

FIG 1

FIG2

FIG3

FIG. 1 is a typical side elevation of an integral hose and nozzle which has substantially circular transverse cross sections throughout and possesses substantially the same appearance when viewed from all sides. The uniform diameter hose portion has been broken away to indicate its indeterminate length.

FIG. 2 is an enlarged view of the incremental area A outlined for purposes of illustration in FIG. 1; and;

FIG. 3 is a sectional view of the incremental area A in FIG. 1.

We claim:

The ornamental design for an integral hose and nozzle, substantially as shown and described.
